CHARLES D. REYNOLDS, OF CRANSTON, RHODE ISLAND.

WINDING-MACHINE.

1,259,448.

Specification of Letters Patent. Patented Mar. 12, 1918.

Application filed July 18, 1916. Serial No. 109,878.

To all whom it may concern:

Be it known that I, CHARLES D. REYNOLDS, a citizen of the United States, residing at Cranston, in the county of Providence, State 5 of Rhode Island, have invented certain new and useful Improvements in Winding-Machines, of which the following is a specification.

My invention relates to winding machines 10 and consists of an improved clutch-mechanism for controlling the operation of the winding-mandrel of the machine combined with means for securing the cop-tube or shell on the mandrel and for releasing it 15 therefrom at the completion of the winding. The object of my improvement is to simplify the mechanism of the machine by providing a single manually-operable means for operating both the cop-tube holder and its 20 clutch-devices whereby the control of the machine is rendered more convenient and its operation more efficient.

The manner and means for carrying out the improvement are fully explained in the 25 following specification, illustrated by the accompanying drawings, in which like reference characters designate like parts. In the drawings:—

Figure 1 is a longitudinal, sectional view 30 of the cop-tube holder or winding-mandrel shown in connection with its clutch-device and the means for manually operating the same;

Fig. 2, a similar view of the tube-holder 35 by itself illustrating its parts in a different relation;

Fig. 3, a detail view of the detent-mechanism of the operating-mechanism for the clutch and holder;

Fig. 4, a detail view of the spring-acting, 40 tube-securing means for the holder; and

Fig. 5, a rear, end view of the tube-holder showing the relation of the tube-securing means thereto.

Referring first to Fig. 1, F designates a portion of the upright frame of the winding machine which is formed with a hub or bearing f for supporting the fixed spindle S for the winding-mandrel H. Preferably 45 the spindle S is constructed of hollow rod or tubing and its end is driven into a bore in the hub f with the greater portion of its length overhanging the side of the frame F. Mounted to rotate freely on the spindle S is 50 a belt-pulley P arranged with its hub p abutting the end of the hub f. Abutting

the outer end of the hub p of the pulley P is a relatively long sleeve or bushing B also free to rotate on the spindle S. The bushing B is held in place on the spindle S by 60 means of a rod R extending through the bore s of the spindle. At its outer end the rod R is formed with, or has secured thereto, a cap r fitted to the end of the bore s and provided with a head or flange r' abutting 65 the end of the bushing B. The opposite end of the rod R is inserted through an axial hole in a cap R', fitted to the inner end of the spindle S, and secured in place by a nut r''. Preferably the cap R' is drilled with 70 an oil-hole r³ to provide for the introduction of lubricant into the bore of the spindle S which serves as an oil-chamber for distributing it through the openings s', s' to the 75 several rotating elements mounted on the spindle.

Fixedly mounted on the outer end of the bushing B is the winding-mandrel or cop-tube holder H which as herein illustrated is made in the form of a truncated cone to 80 adapt it to receive the conical tubes or shells in common use for supporting cone-packages of yarn or thread. Between the cone-tube holder H and belt-pulley P is a clutch-member C adapted to connect the holder to be 85 driven from the pulley. The cone-holder H is chambered or hollowed out at both ends, for the purpose of saving metal and weight, and is bored at h to receive the bushing B to which it is secured by a set-screw h', or 90 through any other suitable means. The rearward end of the solid portion of the holder H abuts the side of an annular flange or collar b on the bushing B, and held therebetween is a spider-like spring-member E 95 preferably formed from flat steel. Referring to Figs. 4 and 5, the spring-member E is constructed with a central, circular plate or ring e fitted over the bushing B and formed with four radial arms e', e' bent at 100 an angle to adapt them to fit within the cored out cavity h² at the base end of the holder H. Adjacent the ends of each arm e' are two triangularly-shaped projections e², e² bent up from their sides to form sharp 105 prongs or teeth adapted to be forced into the paper or fiber cone-tube X which fits over the outside of the holder H, see Fig. 1. Referring particularly to Fig. 5, the rearward end of the shell of the holder H is cut 110 away or slotted longitudinally to provide four lugs or fingers h³ which are straddled

by the teeth e^2 on the arms e' . As shown in Fig. 1, the points of the teeth normally project beyond the peripheral surface of the holder H , due to the spring-action of the 5 arms e' , thereby causing them to bite into the inner surface of the cop-tube X . Referring to Fig. 4, the ends of the arms e' extending rearwardly beyond the teeth e^2 are bent down at an angle to provide the inclined 10 fingers e^3 for engagement with an interiorly-beveled face c^2 of a flange c on the hub c' of the clutch-member C , see Fig. 2. Through this engagement the teeth or prongs e^2 are adapted to be withdrawn from engagement 15 with the interior of the cone-tube or shell X by the depression of the arms e' when the clutch-member C is slid to the left as more fully explained hereinafter.

Referring to Figs. 1 and 2, the clutch-20 member C is of usual type formed with a tapered face c^3 adapted to frictionally engage the corresponding, interior, tapered face p' of the pulley P . The hub c' of the clutch-member C is fitted to slide on the 25 bushing B and extends to the left some distance beyond the flange c to adapt it to reach within the cavity h^2 of the holder H . Surrounding this portion of the hub c' is a coiled spring D which bears at one end 30 against the flange b of the bushing B , and at the other against the flange c of the clutch-member C . Through this means the clutch-member C is maintained normally in engagement with the driving-pulley P by the action 35 of the spring D . The clutch-member C is connected rotatively with the cone-holder H , while being free to slide axially with respect thereto, through the arrangement next described: Referring to Figs. 1, 2 and 5, 40 two lugs h^4 project rearwardly from the base of the holder H and enter opposite slots c^4 cut through the outer rim c^5 of the annular flange c on the hub of the clutch C . It will be noted from Fig. 2 that the rim 45 c^5 extends outwardly some distance beyond the portion of the flange c formed with the beveled face c^2 to adapt it to strike against the base end of the tube X to force the latter off from the holder H after the teeth 50 e^2 of the arms e' have been disengaged from its interior.

The clutch-member C is adapted to be slid on the bushing B to disengage it from the pulley P by means of an arm G pivoted 55 at g on an extension F' of the frame F and reaching up to engage the side of the flange c . The arm G forms a part of the automatic stopping-mechanism of the machine which is operated upon the breaking of the 60 yarn or the exhaustion of the supply during the winding of a package or cone on the holder H . The arm G is also adapted to be operated from a hand-lever K to move the clutch-member to its extreme position 65 to the left, as shown in Fig. 2, to release

the tube-holding means and eject the finished cone from the holder H . The means for operating the arm G automatically forms the subject-matter of a separate application for patent and will not herein be 70 described in detail. As regards the present invention, suffice it to explain that the arm G is normally held inactive in the position illustrated in Fig. 1 through detent-means arranged as next described, and is released 75 by the automatic devices not herein shown.

As illustrated in Fig. 1 the arm G takes the form of a bell-crank-lever, having a horn-shaped extension g' reaching toward the right with its end resting upon the top 80 of a lug l projecting from the hub of a rock-lever L . The lever L is pivoted on a rod m extending at right-angles to the axis of the arm or lever G and held in bearings in the frame-extension F' . Referring to Fig. 85 3, which is a view of the parts looking in the direction indicated by the arrow 3, Fig. 1, the lever L is formed with a shoulder or ledge l' adapted to be engaged by a detent-shoulder n on a lever N . The lever N is pivoted on a cross-pin o arranged below and parallel with the pivot-rod m of the lever L and serves as the prime element for restraining the action of the clutch-releasing means or for effecting its operation 95 when the automatic stop-devices come into play. The lever N is held normally balanced by a relatively light spring U , shown in Fig. 1, to adapt its detent-shoulder n to engage the ledge l' on the lever L when the latter is depressed. The spring U is fastened at n' to the lever N and at its upper end is hooked through a hole g^2 in the arm g' of the lever G . In this manner the spring U has the added function of maintaining the end of the arm g' bearing against the lug l of the lever L . The lever L is operated to swing it upwardly by means of a spring V , see Fig. 1, fastened to a lug l^2 at the end of its arm l^3 and anchored to the frame F at f' . A lug l^4 on the upper side of the arm l^3 is adapted to strike against a cross brace f^2 on the frame-extension F' to limit the upward movement of the lever L under action of its spring V . Through this means the action of the lever L is restricted to an extent just sufficient to move the arm G to carry the clutch-member C out of engagement with the pulley P , but not enough to slide the clutch to release the cop-tube X from the holder H . The purpose of this arrangement is to prevent the ejection of the package from the holder H when the machine is stopped for piecing up the yarn or replenishing its supply, that is, before the package is completed, the method of operation of the parts to secure this end being more fully explained hereinafter.

Pivoted on the same rod g with the arm

G is the hand-lever K, previously referred to, which is formed with a curved handle *k* reaching out in convenient position below the cone-holder H. At its inner end the lever K is provided with two opposite abutments or fingers *k'*, *k''* which straddle the sides of the arm G to adapt the latter to be rocked in either direction from the movement of the handle *k*, while also allowing a slight play therebetween. Reaching back from the hub of the lever K is a curved arm *k⁴* the end of which normally lies above an arcuate extension or arch-member *l⁵* formed at right-angles to the main arm of the lever L, see Fig. 3. When the hand-lever K is raised its arm *k⁴* will be brought down against the top of the arch-member *l⁵* to depress the lever L, and through this action the detent-ledge *l'* on said lever L is brought into engagement with the detent-shoulder *n* on the lever N. In this way the handle *k* may be employed as a starting-lever to effect the operation of the machine after it has been stopped as more fully explained hereinafter. The method of operation of the complete apparatus is as follows:

The driving-pulley P is rotated continuously from a belt, not here shown, passing over its periphery and connected with any suitable source of power, and it is obvious that in place of the pulley P any other type of driving-member could be substituted, such as a gear or friction-wheel. When the machine is at rest the clutch-member C is held free from the pulley P, in the position indicated by the dash-lines, Fig. 1, by means of the arm G bearing against the side of the flange c. The pulley P thus runs free without driving the winding-mandrel or tube-holder H until the machine is prepared for operation as follows: The cone-tube or shell X is first forced snugly onto the holder H, as shown in Fig. 1, and the spurs or prongs *e²* on the arms *e'* are caused to engage its interior through the spring action of the said arms to secure the tube against accidental displacement. The end of the yarn to be wound into the cop or cone is then made fast to the tube X and inserted in the thread-guide, not here shown, which acts to traverse it on the tube in the usual manner during the operation of the machine. To start the machine the operator raises the handle of the lever K, thereby rocking the arm G to the right to free its end from the flange c on the clutch C to allow the latter to be forced into engagement with the pulley P by the action of its spring D. As the hand-lever K is raised as above described its extension or arm *k⁴* is brought down against the top of the arch-member *l⁵* of the lever L and the latter will thereby be rocked against the action of its spring V. Referring to Fig. 3, this latter movement of the

lever L carries its ledge *l'* down into position to be engaged by the shoulder *n* on the detent-lever N, this engagement being effected by the action of the spring U on the lever N. The lever L will thus be locked in place against upward movement by its spring V and meanwhile the arm G is held free from the flange c of the clutch C by the action of the spring U, see Fig. 1. The clutch C will therefore be maintained in engagement with the pulley P under the action of its spring D, and hence the winding-mandrel or tube-holder H connected with the clutch by its lugs *h⁴* will be driven therefrom. The rotation of the holder H causes the yarn leading through the thread-guide to be wound onto the tube X to build it up in the conventional cone-shaped package or cop as usually employed in the art.

When the yarn breaks or its supply is exhausted the automatic stopping-devices which are connected to the detent-lever N act to rock said lever to release its shoulder *n* from the ledge *l'* on the lever L. This release of the lever L allows its spring V to rock it upwardly until its lug *l⁴* strikes against the cross-member *f²* of the frame F'. During this upward movement of the lever L its lug *l* bears against the under side of the arm *g'* of the lever G, see Fig. 3, and thereby rocks the latter to carry the end of its upright arm against the flange c on the clutch C. This causes the clutch C to be slid to the left to disengage its beveled face *c³* from the interior of the pulley P. As before stated, however, the limiting lug *l⁴* on the lever L is arranged to prevent the latter from moving the arm G to slide the clutch C to its full extent. That is to say, the movement of the arm G under action of the lever L is just sufficient to release the clutch C from the pulley P without carrying the beveled face *c²* of its flange c into engagement with the spring-arms or dogs *e'*, see dash lines in Fig. 1. It will therefore be understood that the clutch C is operated automatically to effect the stopping of the tube-holder or mandrel H without releasing the cop-tube from the holder.

When, however, the winding of the cone or package has been completed and it is desired to remove it from the holder H this is accomplished by a manual operation as follows: The operator simply presses down on the handle *k* to rock the arm G farther to the left, thereby carrying the flange c on the clutch C into engagement with the ends of the spring-arms *e'*, as shown in Fig. 2. Continued pressure on the handle *k* causes the beveled face *c²* of the flange c to act on the inclined ends *e³* of the arms *e'* to depress the latter and withdraw the teeth *e²* radially inward to release them from the tube X. Meanwhile the rim *c⁵* of the flange c comes against the end of the tube X and

the latter is forced free of the holder H to adapt the package to be easily doffed therefrom. When another tube X is placed on the holder H, preparatory to winding a new package, the hand-lever K is released and the spring-arms e' will be free to act automatically to allow the teeth e² to make engagement with the tube since the clutch C will have been returned to the position shown 10 by the dash lines in Fig. 1 due to the action of the spring D. In this way the tube is gripped and secured automatically by simply forcing it onto the holder H and to start the rotation of the winding-holder it is only 15 necessary to raise the handle k to allow the clutch to be shifted in the manner as first described.

It will be observed that my improvement provides an extremely simple mechanism for 20 performing the several operations necessary in preparing the machine for winding and for starting or stopping its operation. The single hand-lever K serves not only for starting the machine but also acts as a 25 means for doffing the cop or package and in this way the manual control of the machine is rendered more convenient and its operation more efficient.

Various modifications might be made in 30 the form and construction of the parts of my improved apparatus without departing from the spirit or scope of the invention; therefore, without limiting myself to the exact embodiment shown and described, what 35 I claim is:—

1. In a winding machine, the combination with a winding-mandrel, of means for securing a cop-tube on said mandrel, a clutch-member connected to rotate the mandrel and 40 slideable axially in relation thereto, a driving-member for rotating the clutch-member, and means for sliding the clutch-member to connect it with or disconnect it from the driving-member and to also cause said 45 clutch-member to engage with the cop-tube securing-means to release the latter from the cop-tube.

2. In a winding machine, the combination with a winding-mandrel having means for 50 engaging the cop-tube to secure it thereon, of a driving-member for rotating the mandrel, a clutch-member rotatable with the mandrel and slideable to engage the driving-member, a lever for sliding the clutch-member into and out from engagement with the 55 driving-member, and means to operate said lever manually to slide the clutch-member to engage it with the cop-tube securing-means to release the latter from the cop-tube.

3. In a winding machine, the combination with a winding mandrel, of means on said 60 mandrel for engaging the cop-tube to secure it thereto, a driving-member for rotating the mandrel, a clutch-member rotatively con-

nected with the mandrel to adapt it to be moved in one direction to engage the driving-member and in the opposite direction to act on the cop-tube engaging-means to release the latter from the tube, and means 70 to operate the clutch-member in the manner and for the purpose described.

4. In a winding machine, the combination with a rotatable winding-mandrel, of resiliently-operated means on the mandrel 75 for engaging the cop-tube to secure it thereto, a driving-member for rotating the mandrel, a clutch-member for operatively connecting the mandrel with the driving-member, and means for operating the clutch-member to disengage it from the driving-member and to also cause it to act on the tube-engaging means to release the latter from the tube.

5. In a winding machine, the combination 85 with a rotatable cop-tube holder, of means for securing the cop-tube on the holder, a clutch-member rotatively connected with the tube-holder and movable into engagement with the tube-securing means to operate 90 the latter, a driving-member, means to engage the clutch-member with the driving-member, automatically-operated means for disengaging the clutch-member from the driving-member, and manually-operable 95 means for moving the clutch-member into engagement with the tube-securing means to operate the latter to release the tube.

6. In a winding machine, the combination with a rotatable winding-mandrel, of means 100 on said mandrel for engaging the cop-tube to secure it thereto, a driving-member for rotating the mandrel, a clutch-member rotatively connected with the mandrel to adapt it to be moved thereon to operate the 105 tube-holding means, means for effecting engagement between the clutch-member and the driving-member, automatically-operated means for disengaging the clutch-member and driving-member, and manually-operable 110 means for moving the clutch-member into engagement with the tube holding means to operate the latter to release the tube.

7. In a winding machine, the combination 115 with a rotatable winding-mandrel, of means on said mandrel for securing the cop-tube thereto, a driving-member for rotating the mandrel, a clutch-member slideable in one direction to connect the mandrel with its 120 driving-member and in the opposite direction to engage the tube-securing means to operate the latter, a spring for maintaining the clutch-member in engagement with the driving-member, automatically-operated 125 means to slide the clutch-member to disengage it from the driving-member, and manually-operable means to continue the sliding movement of the clutch-member to release the tube-securing means.

8. In a winding machine, the combination with a rotatable winding-mandrel, of means on said mandrel for securing the cop-tube thereto, a driving-member for rotating the mandrel, a clutch-member slidable in one direction to connect the mandrel with the driving-member and in the opposite direction to engage the tube-securing means to operate the latter, a lever for sliding the clutch-member, automatically-operated means for actuating the lever to release the clutch-member from the driving-member, and manually-operable means for moving the lever to engage the clutch-member with the driving-member and to also move the clutch-member in the opposite direction to release the tube-engaging means.

9. In a winding machine, the combination with a rotatable winding-mandrel, of means on said mandrel for securing the cop-tube thereto, a driving-member, a clutch-member rotatively connected with the mandrel and movable into engagement with the tube-securing means to operate the latter, a spring for forcing the clutch-member into engagement with the driving-member, a lever for releasing the clutch-member from the driving-member, detent-means for normally maintaining said lever inactive, and manually-operable means for moving the lever to operate the clutch-member to release the tube-engaging means.

10. In a winding machine, the combination with a rotatable winding-mandrel, of means on said mandrel for securing the cop-tube thereto, a driving-member for rotating the mandrel, a clutch-member for connecting the mandrel with the driving-member and movable into engagement with the tube-engaging means to operate the latter, means for normally maintaining the clutch-member in engagement with the driving-member, means to release the clutch-member from the driving-member, detent-means for maintaining said clutch-releasing means inoperative, and manually-controlled means to operate the clutch-member to release the tube-securing means after the release of the detent-means.

11. In a winding machine, the combination with a winding mandrel, of means for securing the cop-tube thereon, a driving-member for rotating the mandrel, a clutch-member for connecting the mandrel with the driving-member and movable into engagement with the tube-securing means to operate the latter, a spring to engage said clutch-member with the driving-member, a lever to disengage the clutch-member from the driving-member, and a second manually-controlled lever to operate the first lever to move the clutch-member to disengage the tube-securing means.

12. In a winding machine, the combination with a winding-mandrel, of means for

securing the cop-tube thereon, a driving-member for rotating the mandrel, a clutch-member for connecting the mandrel with the driving-member, said clutch-member movable into engagement with the tube-engaging means to operate the latter, a spring to engage the clutch-member with the driving-member, a lever to disengage the clutch-member from the driving-member, means to operate said lever, detent-means for maintaining said last-named means inactive, and a second hand-lever for moving the first lever after the release of the detent-means to shift the clutch-member in one direction to engage it with the driving-member and in the opposite direction to release the tube-securing means.

13. In a winding machine, the combination with a non-rotatable spindle, of a winding-mandrel rotatable thereon, means on the mandrel for securing the cop-tube thereto, a driving-member rotatable on the spindle, and a clutch-member connected to rotate the mandrel and slidable in one direction to engage the driving-member and in the opposite direction to engage the tube-securing means to operate the latter to release the tube.

14. In a winding machine, the combination with a fixed spindle bored longitudinally to provide an oil reservoir having ports leading therefrom to its exterior, of a winding-mandrel rotatably mounted on the spindle, a driving-member also mounted to rotate on the spindle, and a clutch-member 100 rotatively connected with the mandrel and slidable on the spindle to engage the driving-member.

15. In a winding machine, the combination with a non-rotatable spindle, of a driving-member rotatable thereon, a bushing also rotatable on the spindle, a winding-mandrel fast on said bushing to rotate therewith, and a clutch-member rotatively connected with the mandrel and slidable on the 110 bushing to engage the driving-member.

16. In a winding machine, the combination with a rotatable bushing formed with an annular collar, of a winding-mandrel fixedly secured on the bushing abutting the 115 side of the collar, a spider-like spring secured between the mandrel and collar and formed with arms having radial teeth adapted to engage the interior of a cop-tube fitted to the mandrel, and a clutch-member 120 rotatively connected with the mandrel and slidable on the bushing to depress the arms of the spring to release their teeth from the cop-tube.

17. In a winding machine, the combination with a conical cop-tube holder formed with a recess at one end, of a spider-like spring secured in said recess and formed with arms having radially-projecting teeth adapted to engage the interior of a cop-tube 130

fitted to the holder, a driving member, and a clutch-member slidable axially in one direction to engage the driving-member, said clutch-member formed with a beveled flange 5 adapted to engage the ends of the spring-arms when moved in the opposite direction to release their teeth from the cop-tube.

18. In a winding machine, the combination with a winding-mandrel, of means for 10 securing the cop-tube thereon, a driving-member for rotating the mandrel, a clutch-member for connecting the mandrel with the driving-member and also operable to release the tube-securing means, a lever for operating the clutch-member, a second spring-operated lever for moving the first lever, means for maintaining said second lever 15 normally inoperative, and a third manually-

operable lever for actuating the first lever independently of the second lever.

19. In a winding machine, the combination with a winding-mandrel, of means for 20 securing the cop-tube thereon; a driving-member for rotating the mandrel, a clutch-member for connecting the mandrel with the driving-member and also operable to release 25 the tube-securing means, a lever to operate the clutch-member, spring-operated means for actuating said clutch-lever, detent-means for normally maintaining the spring-operated means inactive, and a hand-lever for 30 operating the clutch-lever when the detent-means are released.

In testimony whereof I affix my signature.

CHARLES D. REYNOLDS.
